SURGICAL TABLE

Weston W. George, Manitowoc, Wis., assignor to Hamilton Manufacturing Company, Two Rivers, Wis., a corporation of Wisconsin

Filed Feb. 28, 1962, Ser. No. 69,010

Term of patent 14 years

(CL. D83—1)

FIG. 1 is a front perspective view of a surgical table embodying my new design;

FIG. 2 is an elevational view of the end of the table not shown in FIG. 1 with portions omitted and fragmentarily shown for ease of illustration; and

FIG. 3 is a sectional view taken on the line 3—3 of FIG. 1.

The side of the table not shown is substantially the same in appearance to the side shown.

The dominant features of my design reside in the portions shown in full lines.

I claim:

The ornamental design for a surgical table, substantially as shown and described.
